UNITED STATES PATENT OFFICE.

CHARLES A. COVEY, OF SAN ANTONIO, TEXAS, ASSIGNOR OF ONE-HALF TO CLAUDE V. BIRKHEAD.

CLAMP.

Application filed June 23, 1927. Serial No. 200,991.

The invention relates to improvements in clamps such as those used by cabinetmakers and it aims to provide a new and improved clamp construction which, while rather simple and inexpensive, will be efficient, quickly and easily adjustable, and generally desirable.

With the foregoing in view, the invention resides in the novel subject matter hereinabove described and claimed, the description being supplemented by the accompanying drawing.

Fig. 1 is a side elevation of a clamp constructed in accordance with my invention, the cam lever being shown in released position.

Fig. 2 is an edge view.

Fig. 3 is a sectional view partly in elevation, the cam lever being shown in operative position in this view.

The drawing above briefly described illustrates the preferred form of construction and while this construction will be herein specifically set forth, it is to be understood at the outset, that within the scope of the invention as claimed, variations may be made.

The numerals 4 and 5 denote two overlapped bars having curved ends 6 provided with appropriate jaws 7 for engagement with the work, the inner ends of said bars being equipped with suitable guides 8 by means of which said bars are slidably connected. These guides are such that the bars 4 and 5 are offset edgewise to some extent and they may also have their flat sides spaced apart somewhat as shown.

An abutment 9 is adjustably engaged with the bar 5 for movement to numerous positions along the length thereof, and in the present showing, an edge of this bar is provided with ratchet teeth 10 to be engaged by a nose 11 of the abutment 9 for the purpose of holding the latter in adjusted position. A suitable spring 12 is carried by abutment 9 and engages the edge of bar 5 remote from the teeth 10, to engage the nose 11 with said teeth, holding the abutment against accidental sliding.

A cam lever 13 is fulcrumed at 14 upon the bar 4, near the inner end of the latter, the cam of this lever being co-operable with the abutment 9 to forcibly draw the bars 4 and 5 inwardly to clamping position after they have been moved into contact with the work and said abutment has been slid along the bar 5 into contact with said cam. In this connection, attention is invited to the fact that Fig. 1 discloses the cam lever in released position near the abutment 9, whereas in Fig. 3, said lever has been swung to an operative position at which it serves to tightly move the jaws 7 into clamping relation with the work, as well as holding said jaws in operative position.

It will be seen from the foregoing that the clamp is rather simple and inexpensive, that it may be quickly and easily adjusted, that it will produce an effective clamping action with ease of operation, and that it will be generally desirable.

The details disclosed are preferably followed, but within the scope of the invention as claimed, variations may be made.

I claim:

1. A clamp comprising overlapped bars having jaws at their outer ends, guides by means of which said bars are slidably connected, an abutment slidable along one bar and adapted to grip the latter at any of a number of points, and a cam lever fulcrumed on the other bar to engage said abutment for the purpose of drawing the two bars and their jaws inwardly into clamping relation with the work.

2. A clamp comprising two overlapped bars having jaws at their outer ends, guides by means of which said jaws are slidably connected, an abutment slidable along one of said bars and adapted to grip the latter at any of a plurality of points, and means movably mounted on the other bar to engage said abutment and forcibly move the bars and their jaws inwardly into clamping relation with the work.

3. A clamp comprising two overlapped bars having jaws at their outer ends, guides

by means of which said jaws are slidably connected, a slide movable along one of said bars and having a nose, one edge of said one bar having teeth co-operable with said nose to hold the slide in adjusted position, a spring carried by the slide and engaging the opposite edge of said one bar to yieldably hold the nose engaged with the aforesaid

teeth, and a cam lever fulcrumed on the other of said bars, said cam lever being co-operable with said slide to draw the two bars and their jaws forcibly inward into clamping relation with the work. ¹⁰

In testimony whereof I have hereunto affixed my signature.

CHARLES A. COVEY.
